UNITED STATES PATENT OFFICE.

CARROLL BEALE, OF WASHINGTON, DISTRICT OF COLUMBIA, ASSIGNOR OF ONE-HALF
TO DAVID FELTON MOORE, OF WASHINGTON, DISTRICT OF COLUMBIA.

PLASTER TIE AND REINFORCEMENT CHAIR.

Application filed September 11, 1923. Serial No. 662,091.

This invention relates to an improved plaster tie and reenforcement chair for reinforced concrete ceiling, floors, walls and the like, wherein it is desirable to apply plaster directly to the concrete, one object of the invention being the provision of a device of this character which is easily and readily placed in position in conjunction with the form boards, which after the removal of such boards will be embedded in the concrete with the ties projected a sufficient distance beyond the surface of the concrete to form a support for the plaster to adhere to.

A further object of this invention is the provision of a device of this character made from sheet metal and so formed as to be easily transported, put into place and manipulated to provide a simple and efficient means for supporting the metal reenforcing rods above the form boards and to provide a projecting tie beyond the face of the coalesced concrete after the boards are removed, the metal ties being easily bent toward the surface to permit of the plaster being applied therearound to adhere thereto, thus making a permanent tying means for the plaster to the concrete.

A still further object of this invention is the provision of a device of this character which is simple and inexpensive to manufacture, easily handled and put in to place so as to be useful and practical, and which will supply a long felt want, in that with it, it is now possible to attach or apply plaster direct to a concrete surface without fear of it falling off.

In the accompanying drawings:—

Figure 1 is a perspective view of the device as it appears ready for insertion.

Figure 2 is a cross section through a reinforced concrete floor with the device and form boards in place.

Figure 3 is a similar view with the form boards removed and the ceiling plastered.

Figure 4 is a plan view of a portion of the blank of the device, prior to bending into the form shown in Figure 1.

Figure 5 is a view similar to Figure 4 of a modified form.

Figures 6 and 7 are plan views of other modified forms in blank.

Figure 8 is a cross section through the form as shown in Figure 7, after the same has been bent into shape.

Referring to the drawings, and more par-

ticularly to Figures 1, through 4, the numeral 10 designates the combined chair and plaster tie C the concrete, R the reinforcing metal rods, T the ties for such rods, and F the form boards.

The device 10 is made from a single sheet of light bendable metal, and is stamped to provide the central body portion 11, the two inwardly converging walls 12, form a V-shaped wedging support or chair, when the substantially circular shaped plaster ties 13, and adjacent as shown, and readily insertible in the spaces s between the form boards F. The openings 14 are arranged in pairs so that when the device is in the position as shown in Figure 2, prior to the concrete being poured, the rods R, may be held against accidental displacement by the metal wire ties T. After the concrete C has coalesced, and the form boards have been removed, the plaster ties 13 will project beyond the surface of the concrete, and these are then bent to assume the position as shown in Figure 3 so that the plaster P may be applied in the usual manner and readily adhere to the concrete and be anchored or tied in place by the metal ties 13, which are further provided each with an opening 15 to form an additional anchoring means for the plaster.

As shown in Figure 4 the ties 13 are in opposite pairs, whereas in Figure 5 the ties 13' are alternated, to provide a single thickness of tie when in the plaster.

In Figure 6 the ties 13'' are dove-tailed shape.

In Figures 7 and 8, the device is formed with the central body portion 16, the plain wall 17, whose lower edge 18 is designed to rest upon the form board, while the other wall 19, is provided with the circular metal ties or projections 20, which are adapted to be projected between the form boards. This type when packed can be nested, and thus be more compact when in shipment.

What I claim, as new, is:

1. A plaster tie having a portion adapted to project from the surface of a form-board upon which concrete is to be placed and having a part adapted to rest upon a form-board, said portion being arranged to be embedded and locked in the concrete, and a plurality of spaced portions designed to extend from said part into a space between adjacent form-boards and to project beyond the concrete a distance substantially equal to

- the desired thickness of plaster, said portions being bendable at their juncture with said portion which is adapted to rest upon the surface of a form-board.
- 5 2. A plaster tie having a portion adapted to project from the surface of a form-board upon which concrete is to be placed and having a part adapted to rest upon a form-board, said portion being arranged to be embedded and locked in the concrete, and a plurality of spaced, perforated portions designed to extend into a space between adjacent form-boards and to project beyond the concrete a distance substantially equal to the desired thickness of plaster, said portions being bendable at their juncture with said portion which is adapted to rest upon the surface of a form-board.
- 10 3. A plaster tie having a flat portion designed to extend into a space between adjacent form-boards and to project from concrete placed on said form-boards to the desired thickness of the plaster, a portion which is arranged to project from the form-boards and to be embedded and locked in concrete placed on said form-boards, and an intermediate part arranged to engage at least one of said form-boards to limit the degree of the aforesaid extension.
- 15 4. A plaster tie having a flat, perforated portion designed to extend into a space between adjacent form-boards and to project from concrete placed on said form-boards to the desired thickness of the plaster, and a portion which is arranged to project from the form-boards and to be embedded and locked in concrete placed on said form-boards.
- 20 5. A plaster tie having a flat, perforated portion designed to extend into a space between adjacent form-boards and to project from concrete placed on said form-boards to the desired thickness of the plaster, a portion which is arranged to project from the form-boards and to be embedded and locked in concrete placed on said form-boards, and an intermediate part arranged to engage at least one of said form-boards to limit the degree of the aforesaid extension.
- 25 6. A plaster tie having a flat, perforated portion designed to extend into a space between adjacent form-boards and to project from concrete placed on said form-boards to the desired thickness of the plaster, and a portion which is arranged to project from the form-boards and to be embedded and locked in concrete placed on said form-boards, and means for fastening a tie-rod to the portion which is arranged to be embedded in the concrete.
- 30 7. A plaster tie having a flat, perforated portion designed to extend into a space between adjacent form-boards and to project from concrete placed on said form-boards, a part which is arranged to project from the form-boards and to be embedded and locked in concrete placed on said form-boards, an intermediate part arranged to engage at least one of said form-boards to limit the degree of the aforesaid extension, and means for fastening a tie-rod to the portion which is arranged to be embedded in the concrete.
- 35 8. The herein described method of bonding a covering coat directly onto a concrete structure which consists of assembling form-boards, then placing a suitable mechanical tie on the form-boards with a portion thereof extending into a space left between adjacent form-boards without special preparation of the boards, surrounding and locking into a body of concrete a portion of the mechanical tie, by placing concrete on the form-boards, removing the form-boards, and thereafter spreading a covering coat onto the concrete and over the portion of the tie which projects therefrom.

45 form-boards and to be embedded and locked in concrete placed on said form-boards, and an intermediate part arranged to engage at least one of said form-boards to limit the degree of the aforesaid extension.

50 6. A plaster tie having a flat, perforated portion designed to extend into a space between adjacent form-boards and to project from concrete placed on said form-boards to the desired thickness of the plaster, a portion which is arranged to project from the form-boards and to be embedded and locked in concrete placed on said form-boards, and means for fastening a tie-rod to the portion which is arranged to be embedded in the concrete.

55 7. A plaster tie having a flat, perforated portion designed to extend into a space between adjacent form-boards and to project from concrete placed on said form-boards, a part which is arranged to project from the form-boards and to be embedded and locked in concrete placed on said form-boards, an intermediate part arranged to engage at least one of said form-boards to limit the degree of the aforesaid extension, and means for fastening a tie-rod to the portion which is arranged to be embedded in the concrete.

60 8. The herein described method of bonding a covering coat directly onto a concrete structure which consists of assembling form-boards, then placing a suitable mechanical tie on the form-boards with a portion thereof extending into a space left between adjacent form-boards without special preparation of the boards, surrounding and locking into a body of concrete a portion of the mechanical tie, by placing concrete on the form-boards, removing the form-boards, and thereafter spreading a covering coat onto the concrete and over the portion of the tie which projects therefrom.
